CLAIM

The ornamental design for a wireless remote controller, as shown and described.

DESCRIPTION

FIG. 1 is a front perspective view of a wireless remote controller, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines illustrating portions of the wireless remote controller form no part of the claimed design. The dot dash lines in the figures represent an unclaimed boundary line and form no part of the claimed design.
